CLAIM

The ornamental design for a knife handle, as shown and described.

DESCRIPTION

FIG. 1 is a front perspective view of a knife handle;

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof; and,

FIG. 7 is a bottom plan view thereof.

The dot-dash lines are provided to show the boundary of the claim and form no part of the claim. The dash-dash lines show portions of a knife handle in which the design is embodied that are not considered part of the claimed design.

1 Claim, 5 Drawing Sheets(56)
